UNITED STATES PATENT OFFICE.

HUGH C. LORD, OF ERIE, PENNSYLVANIA.

SECTIONAL BOOKCASE OR LIKE ARTICLE OF FURNITURE HAVING PARTS SLIDING IN AND OUT THEREIN.

SPECIFICATION forming part of Letters Patent No. 762,071, dated June 7, 1904.

Application filed September 29, 1902. Serial No. 125,268. (No model.)

To all whom it may concern:

Be it known that I, HUGH C. LORD, a citizen of the United States, residing at Erie, in the county of Erie, State of Pennsylvania, have 5 invented certain new and useful Improvements in Sectional Bookcases or Like Articles of Furniture Having Parts Sliding in and out Therein, of which the following is a description, reference being had to the accompanying drawings, and to the letters of reference marked thereon.

This invention relates to sectional bookcases and like articles of furniture having parts sliding in and out therein; and it consists of certain improvements in the construction thereof, as will be hereinafter fully described, and pointed out in the claims.

The invention is peculiarly adapted to sectional bookcases having doors arranged to slide back under the tops of the sections, and the invention, as illustrated, is applied to such a section.

In the drawings, Figure 1 shows a front elevation, partly in section, of the section; Fig. 2, a sectional fragment showing the hinge for a portion of the paralleling device; Fig. 3, an enlarged perspective view of the door-hinge; Fig. 4, a perspective view of the paralleling mechanism; Fig. 5, a section on the line 5-5 of Fig. 1.

A marks the bottom of the section, which is preferably of the ordinary two-part construction, B B the sides of the section, and C the top, the top being preferably arranged to 35 enter between the bottom pieces of a superimposed section, as commonly.

D marks the door. The door is hinged on the pintle E, the pintle being preferably provided with a roller e. The hinge d is formed 40 of the plate d', having a perforation d'', through which a screw is passed into the door. One side of the plate is bent up, forming the lug d'', which abuts against the roller e, forming a support for the door.

Extending from the opposite side of the plate d' is a lug d', having a perforation preferably concentric with the pintle E when the door is in its closed position. The door is to be lifted as commonly in this class of cases 50 and slides back between the ends B B, the

door riding on the roller e. The top piece C is provided with two grooves c c, and arranged in these grooves are the paralleling rods F F. These rods are preferably formed by bending sheet-metal strips into the form of tubes. At 55 the ends of the tubes so formed the strips are extended and bent down, forming arms f f. The lower ends of the arms are connected with a supporting-link I at the points i i, and the link I is hinged at i' in the perforation of the 60 lug d'. The rods F are supported in the grooves by the staples G, which are driven into the end of the top C, the lower end g of the staple extending into the end of the tubular rod F. The staple has a shoulder g'. 65

A spring H is arranged on the portion g of the staple, one end of the spring extending through the tube, and thus locking it with the tube, and the opposite end of the spring being tensioned against the shoulder g'. The spring 70 is tensioned to exert force on the arms f f in a rearward direction, so that when the door is raised to a horizontal plane the springs acting through arms f f and link I draw the door back. 75

It will be noted that as one end of the door is moved it acts through the link I, arms f, and rods F upon the similar mechanism at the opposite side of the door, thus carrying the opposite side of the door in parallel relation 80 with that side or end initially moved. It will also be noted that it effects this action on the door when the end of the door is moved either in or out.

The distance between the rods F F, length 85 of the arms f f, distance between the points i i, and length of the link I should be so proportioned that the direction of travel of the point i' will be in substantially a straight line. This proportion may be readily ascertained by a few experiments. The relation of parts shown in Fig. 5 will accomplish approximately this result. 90

It will be noted that the rear end of the door as it moves backward is entirely supported by the link I and arms f f, so that all friction due to the weight of this end of the door is entirely obviated. It will also be noted that the link-and-arm construction prevents the upward movement of the end of the 100

door as it is moving backward, due to the weight of the front end of the door in front of the pivot formed by the lug E.

What I claim as new is—

- 5 1. In a sectional bookcase or like article of furniture, having a part sliding in and out therein, the combination with the frame in which said part slides, of a paralleling device, comprising an oscillating rod mounted in the frame and arranged to permit movement of the sliding part of the rod, rock-arms controlled by said rod, said rock-arms being arranged at each side of the sliding part, the sliding part moving between said arms and links connecting the rock-arms with the sliding part, said links having a pivotal connection with one end of the rock-arms, and a pivot connection with the sliding part.
- 10 2. In a sectional bookcase having a door arranged to slide in the case, the combination with the frame of said case and said door, of a rod extending across the top of the case, said rod being arranged to permit the passage of the door by the rod, rock-arms controlled by said rod and extending downwardly below the plane of the door, as it is moved into the case, said arms being a distance apart at least equal to the length of the door and links connecting said arms with the door.
- 15 3. A sectional bookcase or like article of furniture having a part sliding in and out therein, in combination with the frame in which said part slides, and the sliding part, of a paralleling device, comprising an oscillating rod mounted in the frame, rock-arms controlled by said rod, links connecting said rock-arms to the sliding part, and means to control the action of said links to carry a part of the weight to the sliding part in both the inward and outward movement of the sliding part.
- 20 4. In a sectional bookcase or like article of furniture having a part sliding in and out therein; the combination with the frame in which said part slides; and the sliding part; of a paralleling device comprising an oscillating rod; a connection between said sliding part and the frame through said oscillating rod; said connection comprising rock-arms on said rod and links, and means arranged to control the action of said links to carry a portion of the weight of the sliding part in both the inward and outward movement of the sliding part.
- 25 5. A sectional bookcase or like article of furniture, having a part sliding in and out therein; the combination of the frame in which said part slides; and the sliding part; of a paralleling device comprising an oscillating rod mounted in the frame; rock-arms on said rod; links connecting said rock-arms with the sliding part, and means arranged to control the action of said links to carry a part of the weight of the sliding part in both the inward and outward movement of the sliding part.
- 30 6. In a sectional bookcase or like article of

furniture having a part sliding in and out therein; the combination with the frame in which said part slides; and said sliding part; of a paralleling device comprising an oscillating rod mounted on the frame; links connecting said oscillating rod with the sliding part; and means acting independently of the sliding part for guiding that part of the link connected with the sliding part in a substantially straight line in both the inward and outward movement of the sliding part.

7. In a sectional bookcase or like article of furniture having a part sliding in and out therein; the combination with the frame in which said part slides; and the sliding part; of a paralleling device comprising a rod mounted on the frame and arranged to permit the passing of the sliding part by said rod; rock-arms on said rod at each side of the sliding part, said sliding part being arranged to move between said arms; links connecting said rock-arms with the sliding part; and means independent of said sliding part for guiding the end of said link connected with the sliding part in a straight line.

8. In a sectional bookcase or like article of furniture having a part sliding in and out therein; the combination with the frame in which said part slides; and said sliding part; of a paralleling device comprising an oscillating rod mounted on the frame; links connecting said oscillating rod with the sliding part; and means acting independently of said sliding part for guiding that part of the link connected with the sliding part in a substantially straight line; said links being arranged to carry a part of the sliding part.

9. In a sectional bookcase or like article of furniture having a part sliding in and out therein; the combination with the frame in which said part slides; and said sliding part; of a paralleling device comprising an oscillating rod mounted on the frame; links connecting said arm with said sliding part; and pivoted arms connected with said links and forming guides for directing the movement of the ends of the links to that of a substantially straight line.

10. In a sectional bookcase or like article of furniture having a part sliding in and out therein; the combination with the frame in which said part slides; and sliding part; a rod F having the arms f, f; the links I connecting said arms with the sliding part; and the rock-arms pivotally connected with the frame and with said links, and arranged to direct the movement of the ends of said links in a substantially straight line.

11. In a sectional bookcase or like article of furniture having a part sliding in and out therein; the combination with the frame in which said part slides; and the sliding part; of a paralleling device comprising two oscillating rods; rock-arms on said rods; and links connecting said rock-arms with each other and

with the sliding part; the relative distances between the rods and points of support of the links and connections with the sliding part being such as to give to the ends of the links 5 a movement in substantially a straight line.

12. In a sectional bookcase or like article of furniture having a part sliding in and out therein; the combination with the frame in which said part slides; and the sliding part; 10 of a paralleling device comprising two oscillating rods; rock-arms *f, f, f, f*; the links *I* connecting with the rock-arms and with the sliding part; the distance between the rods *F, F*, the distance between the points of connection 15 between the links and the arms *f, f* and between the points of connection with the arms *f, f*, the ends of the link being such as to direct the end of the link in a substantially straight line; the sliding part being arranged 20 to be partially supported by its connection with the link *I*.

13. In a sectional bookcase or like article of furniture having a part sliding in and out therein; the combination with the frame in 25 which said parts slide; and the sliding part; of the rock-arms *f, f, f, f*, pivotally connected with the frame; and the links *I*, connecting the rock-arms with the sliding part; the distance between the points of pivotal support 30 and between the points of connection of the arms with the link and the length of the link being such as to give to the end of the link a substantially straight line; and the sliding part being arranged to be partially supported by 35 the link.

14. The combination of a bookcase, a door movable from a vertical position into a horizontal position, and in a horizontal position into the case, supports for the door when in 40 its horizontal position, a rod rotatively mounted on the case above the door when the door is in its horizontal position, said rod extending across the case in the lengthwise direction of the case, means controlled by the rod and 45 connected with the in or under side of the door for compelling an equalizing movement of the door, said rod and means being arranged to permit the movement of the door into the case past said rod.

15. In a sectional bookcase having a door arranged to slide in the case, the combination with the frame of said case, and said door; of a rod extending across the top of said case, said rod being arranged to permit the passage 55 of the door by the rod; rock-arms secured to said rod and extending downwardly below the plane of the door as it is moved into the case, said arms being of sufficient distance apart to permit the movement of the door between 60 them; and links connecting said arms with the door.

16. In a sectional bookcase having a door arranged to slide therein, the combination with the frame and said door, the inner face of the 65 top of said frame being provided with a groove

extending from side to side of said frame; of a rod arranged in said groove; rock-arms extending from said rod downwardly below the path of the movement of the door in the case, said rock-arms being at a distance apart to 70 permit the movement of the door between them; and links connecting the rock-arms with the door.

17. In a sectional bookcase having a door arranged to slide in the case, the combination 75 with the frame of said case, and said door; of a rod extending across the top of said case, said rod being arranged to permit the passage of the door by the rod; rock-arms secured to said rod and extending downwardly below the 80 plane of the door as it is moved into the case, said arms being of sufficient distance apart to permit the movement of the door between them; links connecting said arms with the door; and means connected with the links for 85 guiding the ends of the links in connection with the door in a fixed line of travel, the links being arranged to support that part of the door to which they are connected.

18. In a sectional bookcase or like article of 90 furniture having a part sliding in and out therein; the combination with the frame in which said part slides; and the sliding part; a paralleling device comprising an oscillating rod mounted on the frame; rock-arms on said 95 rod; links connecting said rock-arms with the sliding part; and a spring for oscillating said rod in one direction.

19. In a paralleling device for sectional 100 bookcases and like articles of furniture having a part sliding in and out therein; the combination with a tubular rod; of the staple *G* extending into the end of the tube; and the spring *H* arranged on the staple and within the tube. 105

20. In a sectional bookcase having the bottom arranged in two parts; the sides with the recesses *b*; and the top with a part arranged to fit between the parts of the bottom, said top having the grooves *c* therein; the door *D*; 110 the pintles *E*; the hinge *d* supporting the door on the lugs; rods *F* arranged in the grooves *c*; supports for said rods; springs for actuating said rods; the arms *f, f, f, f*, secured to said rods and extending into the recesses *b*; and the links *I* extending from the arm *f* to the hinge; the connection between the link *I* and the hinge being substantially concentric with the pintles *E*, with the top in closed position. 115

21. The combination of a bookcase, a door movable from a vertical position into a horizontal position and in a horizontal position into the case, supports for the door when in its horizontal position, rock-arms, devices secured to the case in front of the back thereof for supporting said arms, means connecting said arms with the in or under side of the door, and means for compelling said arms to move together, said arms, devices and means 125 130

being arranged to permit the movement of the door into the case past said supporting devices.

22. The combination of a bookcase, a door movable from a vertical position into a horizontal position, supports for the door when in its horizontal position, a rod extending in the lengthwise direction of the door, each end of the rod supporting an arm at substantially

right angles thereto, and a link for each arm having a pivotal connection with the arms and a pivotal connection with the door.

In testimony whereof I affix my signature in presence of two witnesses.

HUGH C. LORD.
